(57) **CLAIM**

The ornamental design for an inflator as shown and described.

DESCRIPTION

FIG. 1 is a top perspective view of an inflator embodying my new design;

FIG. 2 is a top perspective view of the inflator of FIG. 1;

FIG. 3 is a top view of the inflator of FIG. 1;

FIG. 4 is a bottom view of the inflator of FIG. 1;

FIG. 5 is a front view of the inflator of FIG. 1;

FIG. 6 is a rear view of the inflator of FIG. 1; and,

FIG. 7 is a left-side view of the inflator of FIG. 1; the right-side being a mirror-image thereof and therefore not shown.

The broken lines show portions of the inflator not claimed and form no part of the claimed design.
